UNITED STATES PATENT OFFICE.

FREDERICK H. HANSEN AND THOMAS THOMPSON, OF JOLIET, ILLINOIS.

COMBINATION TIE-PLATE AND RAIL-ANCHOR.

1,159,838.

Specification of Letters Patent.

Patented Nov. 9, 1915.

Application filed June 10, 1915. Serial No. 33,257.

To all whom it may concern:

Be it known that we, FREDERICK H. HANSEN and THOMAS THOMPSON, citizens of the United States, residing at Joliet, in the county of Will and State of Illinois, have invented new and useful Improvements in Combination Tie-Plates and Rail-Anchors, of which the following is a specification.

This invention relates particularly to a combination tie-plate and rail-anchor for securing a rail to a tie; and the primary object is to provide a device of improved and durable construction and increased security.

The invention is illustrated in its preferred embodiment in the accompanying drawings, in which—

Figure 1 represents a broken plan view of a railway tie having applied thereto our improved combination tie-plate and rail anchor, the rail being indicated by dotted lines; Fig. 2, a section taken as indicated at line 2 of Fig. 1, this view showing the rail in place; Fig. 3, a section taken as indicated at line 3 of Fig. 1, the rail being shown in place; and Fig. 4, a broken sectional view, taken as indicated at line 4 of Fig. 1.

In the illustration given, A represents a tie or sleeper; B, an improved combination tie-plate and rail-anchor applied to said tie; and C, a rail mounted on the device B and securely anchored to the tie through the medium thereof.

The device B comprises a plate 1 mounted on the tie A, said plate being provided near one lateral edge with a rail-base embracing flange 1^a and being provided near the other lateral edge with an oblique key-way 1^b having parallel sides and which partially underlies one edge-portion of the rail-base; and a wedge-member 2 having parallel sides and a rail-embracing flange 2^a parallel with the flange 1^a and an oblique base-portion 2^b affording a key which is received in the key-way 1^b and partially underlies the rail-base. As thus described, the plate 1 has a central bearing surface 3 for the rail-base, in which, near one lateral edge of the plate, is the oblique key-way 1^b. The construction is such as to afford a recess 4 between the flange 1^a and the

body of the plate 1, and to afford a recess 5 between the flange 2^a and the base-portion of the wedge-member 2. These recesses extend parallel with the rail and conform to 55 the flanges of the base of the rail. The plate 1 is provided at its lateral edges with vertical channels 6, through which the spikes 7 extend into the tie. The flange 1^a is shown strengthened by reinforcing ribs 1^c; 60 and the flange 2 is shown strengthened by reinforcing ribs 2^c. It will be understood, however, that the parts may be made suitably strong in any desired manner. It is preferred to provide the member 2 with 65 laterally-projecting stop-lugs 2^d which engage the corresponding spikes 7 and prevent the wedge-member 2 from working loose. The advance end of the member 2 may also be provided with a lug 2^e which, 70 after the wedge is driven home, may be bent down to engage the edge of the plate 1 in the manner shown in Fig. 3, thus tending to prevent retraction of the wedge-member. It will be understood, however, that either 75 the lugs 2^d or the lug 2^e may be dispensed with, the function of these lugs being the same.

It will be understood that the plate 1 is strongly secured to the tie A by the spikes 80 7. It is preferred, however, to provide one end of the plate 1 with a substantial depending lug or toe 1^d adapted to engage the rear vertical surface of the tie A, in the manner shown in Fig. 2. 85

Where the improved combination tie-plate and rail-anchor is used in connection with a railroad where the traffic is principally in the direction indicated by the arrow in Fig. 2, the device is applied in such a manner 90 that the wedge-member 2 is driven home in the direction indicated by the arrow in Fig. 2, while the toe 1^d of the plate 1 engages the rear side of the tie. In applying the device, a sledge-hammer may be employed 95 to drive the wedge-member 2 home, the blows being received by the shoulder 8 at the rear end of the wedge-member. It may be explained that the device is applied so as to grip the rail securely, so that as the 100 rail expands in the direction of the traffic, the rail will drag the tie through the me-

dium of the combination tie-plate and rail-anchor, the brunt of the stress upon the tie being borne by the substantial toe-piece 1, which relieves the strain upon the spikes.

5. The plate 1 and wedge-member 2 may be of cast-metal, preferably malleable iron.

It will be noted that the key-way 1^b is provided with overhanging shoulders, being shown as a dovetailed key-way, the base-10 portion of the member 2 conforming thereto. Thus, the wedge-member 2 is firmly secured against vertical movement with relation to the plate 1, and, moreover, has the upper surface of its base-portion flush with the 15 rail-bearing surface 3 of the plate 1 and underlying one edge-portion of the base of the rail. The construction is simple, thoroughly durable and serves to anchor the rail to the tie in the most secure manner.

20. The foregoing detailed description has been given for clearness of understanding only, and no unnecessary limitation should be understood therefrom, but the appended claims should be construed as broadly as 25 permissible, in view of the prior art.

What we claim as new, and desire to secure by Letters Patent, is—

1. The combination with a tie and rail, of a combination tie-plate and rail-anchor, 30 comprising a plate surmounting the tie and having a central bearing for the rail base, said plate having near one edge a rail-base-embracing flange and near the other edge an oblique key-way having parallel sides and partially underlying the rail, a wedge-member having an oblique base portion 35 forming a key received in said key-way and partially underlying the rail and having a rail-base-embracing flange parallel with said first-named flange, and spikes extending through channels in the lateral edge-portions of said plate into said tie.

2. A combination tie-plate and rail-anchor, comprising a plate having its edge-45 portions provided with vertical spike-channels and one end provided with a depending tie-engaging toe, said plate having near one edge a rail-base-engaging flange and near the other edge an oblique guide-slot having parallel sides and a wedge-member having an oblique base-portion engaging said guide-slot and a rail-base-embracing flange parallel with said first-named flange.

3. A combination tie-plate and rail-anchor, comprising a plate having a central rail-bearing surface and a rail-embracing flange at one side thereof, said plate having its lateral edge-portions provided with spike-channels and having also near the 60 edge opposite said flange an oblique key-way having parallel sides and intercepting the rail-bearing surface, and a wedge-member having a base-portion forming a key received in said key-way and having a rail-

embracing flange parallel with said first-named flange.

4. A combination tie-plate and rail-anchor, comprising a plate having a central rail-bearing surface and a rail-embracing flange at one side thereof, said plate having its lateral edge-portion provided with spike-channels and having also near the edge opposite said flange an oblique key-way having parallel sides and intercepting the rail-bearing surface, and a wedge-member having a base-portion forming a key received in said key-way and having a rail-embracing flange parallel with said first-named flange, said wedge-member having a lug adapted to prevent retraction of the 80 wedge-member.

5. The combination with a tie and rail, of a combination tie-plate and rail-anchor, comprising a plate surmounting the tie and having a central bearing for the rail-base, 85 said plate having at one end a depending tie-engaging toe and having near one lateral edge a rail-base-embracing flange and near the other edge an oblique key-way having parallel sides and partially underlying the 90 rail and inclining toward the longitudinal axis of the plate in a direction away from said toe, a wedge-member having an oblique base-portion forming a key received in said key-way and partially underlying the rail 95 and having a rail-base-embracing flange parallel with said first-named flange, and spikes extending through channels in the lateral edge-portions of said plate into 100 said tie.

6. The combination with a tie and rail, of a combination tie-plate and rail-anchor, comprising a plate surmounting the tie and having a central bearing for the rail-base, said plate having at one end a depending tie-engaging toe and having near one lateral edge a rail-base-embracing flange and near the other edge an oblique key-way having parallel sides and partially underlying the rail and inclining toward the longitudinal 110 axis of the plate in a direction away from said toe, a wedge-member having an oblique base-portion forming a key received in said key-way and partially underlying the rail and having a rail-base-embracing flange 115 parallel with said first-named flange, spikes extending through channels in the lateral edge-portions of said plate into said tie, and a laterally-projecting lug carried by said wedge-member and engaging one of said 120 spikes.

7. The combination with a tie and rail, of a combination tie-plate and rail-anchor, comprising a plate surmounting the tie and having a central bearing for the rail-base, 125 said plate having near one edge a rail-base-embracing flange and near the other edge an oblique key-way partially underlying the

5 rail, a wedge-member having an oblique base-portion forming a key received in said key-way and partially underlying the rail and having a rail-base-embracing flange parallel with said first-named flange, spikes extending through channels in the lateral edge-portion of said plate into said tie, and an outwardly-projecting lug carried by said wedge-member and engaging a spike on the advance side thereof.
